UNITED STATES PATENT OFFICE.

JAY D. BRUNNER, OF LOS ANGELES, CALIFORNIA.

CONCRETE FLUE-VENT.

1,297,652.

Specification of Letters Patent. Patented Mar. 18, 1919.

Application filed June 20, 1918. Serial No. 241,034.

To all whom it may concern:

Be it known that I, JAY D. BRUNNER, a citizen of the United States, residing at Los Angeles, in the county of Los Angeles and 5 State of California, have invented new and useful Improvements in Concrete Flue-Vents, of which the following is a specification.

My invention relates to concrete flue vents 10 and consists in the novel features herein shown, described and claimed.

Primarily my object is to make a concrete 15 sectional flue vent for use with all kinds of gas burning appliances and to make the sections so that they may be easily matched together and bonded to make the pipe impervious to the gases escaping from the gas flame.

Figure 1 is a side elevation of a piece of 20 flue vent embodying the principles of my invention, parts being broken away and shown in section.

Fig. 2 is an enlarged lower end perspective 25 of one of the concrete sections and showing the joint construction.

Fig. 3 is a fragmentary perspective of the 30 upper end of a concrete section and showing the joint construction which mates with the construction shown in Fig. 2.

Fig. 4 is an enlarged fragmentary sectional detail on the line 4—4 of Fig. 1.

In constructing a flue vent in accordance 35 with the principles of my invention, concrete pipe sections 1, 2 and 3 are matched and bonded together end to end to produce the desired length of pipe and the desired shape. As shown, the sections 2 and 3 are forty-five degree elbows. The concrete pipe sections are made of a good grade of concrete and are preferably rectangular in cross-section. Each section, whether straight or an elbow, is formed with a lower end 4 adapted to fit upon the upper end 5 of an adjoining section. In other words, each section 40 has a lower end 4 and an upper end 5, the lower end of one section fitting the upper end of the section below.

The outer upper end face 6 of the section 45 1 extends from the outer side face 7 about one-third of the way to the inner side face 8, and the inner end face 9 extends from the inner side face 8 about one-third of the way to the outer side face 7, and the inclined face 10 connects the outer side of the inner end 55 face 9 to the inner side of the outer end face 6 at an angle of about thirty degrees

relative to the side faces, the area of the inclined face 10 being substantially equal to the combined areas of the end faces 6 and 9.

The lower outer end face 11 of the section 2 fits the upper outer end face 6 of the section 1, the lower inner end face 12 of the section 2 fits the inner upper end face 9 of the section 1, and the bevel face 13 of the section 65 2 fits the bevel face 10 of the section 1.

In setting up the pipe sections a sufficient coating of heavy cement is applied to the faces 6, 9 and 10 of the section 1 and the section 2 is pressed downwardly firmly into 70 place, the bevel faces 10 and 13 serving to line the sections to bring their outer faces into position to make a smooth pipe and said bevel faces making a tapered joint connection which will tighten up as the section 2 75 is pressed into place more or less as desired, thereby taking the pressure off of the cement between the faces 12 and 9 and the faces 6 and 11.

By reference to Fig. 4 it will be seen that 80 the faces 10 and 13 come together before the faces 6 and 11, and 9 and 12 come together. The cement 14 between the faces 10 and 13 will fit the unevenness of the faces and if the sections are pressed tightly together this 85 cement will be pinched out at the points of contact and at the time that the sections are set the faces 6 and 11, and 9 and 12 will be spaced apart and a considerable body 15 of the cement will remain between the faces 90 9 and 12 and a similar body 16 will remain between the faces 6 and 11 and then when the cement has bonded and hardened the flue vent will be as solid and impervious as though it were all cast integral.

Heretofore it has been usual to use half-lap joints but in this half-lap square cornered construction it is impossible to get the bodies 15 and 16 of cement in the finished job.

The products of combustion have no effect 100 upon the structure of my flue vent and cannot escape through the wall of the flue vent.

Thus I have produced a concrete flue vent formed of concrete pipe sections, each section 105 having a female end and a male end, the female end of one section fitting the male end of another section, a female end and a male end forming a half-lap joint the intermediate faces of which are tapered and the 110 outer and inner faces of which are flat, the tapered faces being adapted to tighten upon

each other before the flat faces come together, so as to line up the sections and leave spaces between the flat faces for cement, and cement in the spaces.

5 I claim:

A section of concrete flue vent comprising two concrete pipes mounted end to end; the meeting end of one pipe having an end face extending at right angles to the outer side 10 face and about one-third of the way across, a second end face extending at right angles to the inner side face about one-third of the way across, and a third end face connecting the inner ends of the first and second 15 end faces at an angle of about 30° ; the meeting end of the other pipe having an end face extending at right angles to the outer side

face and about one-third of the way across, a second end face extending at right angles to the inner side face about one-third of the way 20 across, and a third end face connecting the inner ends of the first and second end faces at an angle of about 30° ; one meeting end being male and the other meeting end being female; the inclined face of one meeting end fitting and tightening up upon the inclined face of the other meeting end to make a half-lap; and the parts being proportioned, so that the inclined faces will come tight together and hold the flat faces from coming 30 together.

In testimony whereof I have signed my name to this specification.

JAY D. BRUNNER.
